(57) **CLAIM**

The ornamental design for a storage box, as shown and described.

DESCRIPTION

FIG. 1 is a front, right and top perspective view of a storage box showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of portion 9 shown in FIG. 1;

FIG. 10 is a partial enlarged view of portion 10 shown in FIG. 1;

FIG. 11 is a front, right and top perspective view of the storage box in the first use state;

FIG. 12 is a rear, left and bottom perspective view thereof;

FIG. 13 is a front, right and top perspective view of the storage box in the second use state; and,

FIG. 14 is a rear, left and bottom perspective view thereof. The dash-dash broken lines depict portions of the storage box that form no part of the claimed design. The remaining dash-dash broken lines showing additional storage boxes and wheels in FIGS. 11-14 depict environmental subject matter that form no part of the claimed design. The dash-dot broken lines depict enlargements boundary limits that form no part of the claimed design.

1 Claim, 14 Drawing Sheets
